CLAIM

The ornamental design for a device for monitoring and controlling personal lifestyle, as shown and described.

DESCRIPTION

FIG. 1 is a perspective view of an embodiment of a device for monitoring and controlling personal lifestyle showing the new design

FIG. 2 is a right side view thereof;
FIG. 3 is a bottom view thereof;
FIG. 4 is a left side view thereof;
FIG. 5 is a front view thereof;
FIG. 6 is a back view thereof; and,
FIG. 7 is a top view thereof.

The broken lines in the drawings depict portions of the device for monitoring and controlling personal lifestyle, that form no part of the claimed design.

1 Claim, 7 Drawing Sheets

Related U.S. Application Data

a division of application No. 29/649,333, filed on May 29, 2018, now Pat. No. Des. 884,502.
